UNITED STATES PATENT OFFICE.

WILLARD E. DOW, OF BRAINTREE, MASSACHUSETTS.

SPARKING-CIRCUIT CONTROLLER FOR EXPLOSION-ENGINES.

No. 888,597.

Specification of Letters Patent.

Patented May 26, 1908.

Application filed February 8, 1904. Serial No. 192,481.

To all whom it may concern:

Be it known that I, WILLARD E. Dow, a citizen of the United States, and resident of Braintree, in the Commonwealth of Massachusetts, have invented an Improved Sparking-Circuit Controller for Explosion-Engines, of which the following description, in connection with the accompanying drawings, is a specification.

My invention is particularly adapted to high-speed service, such as is required in connection with gas-engine igniters, and the like, the leading objects thereof being to provide quick and sensitively responsive action, smooth running in either direction, simple and durable construction, and economy of cost and operation.

The constructional details and operation, together with further advantages thereof, will be pointed out in the course of the following description, reference being had to the accompanying drawings.

In the drawings Figure 1 is a perspective view of a preferred embodiment of my invention, the removable cap being broken away for clearness of disclosure. Fig. 2 is a front elevation thereof. Fig. 3 is a sectional view taken on the line 3—3, Fig. 2. Fig. 4 is a fragmentary perspective view, showing a modified construction. Figs. 5—7 are diagrammatic views, illustrating various adaptations in use.

It will be understood that my present invention is adapted to general use although specially intended for use with sparking circuits of gas-engines.

Mounted in a suitable back-plate *a* are one or more sets of contacts *a¹*, *a²*, four sets being shown for convenience of illustration, the movable members, or spring contact-makers, *a¹* being carried by posts *a³* extending from the plate *a*, and the stationary members *a²* being adjustably carried in posts *a⁴*, insulated at *a⁵* and provided with binding screws *a⁶* at the rear of the back-plate. Cooperating with said sets of contacts, is a rotary interrupter, centrally journaled in the back-plate, and comprising a disk *a⁷* fast on a hub *a⁸* of a shaft *a⁹*, the latter being the engine shaft, in a 2-cycle engine, or an auxiliary shaft in a 4-cycle engine. The disk *a⁷* has lateral flanges *a¹⁰*, *a¹¹*, preferably peripheral, and in the recess between them I mount one or more small tripping wheels, *a¹²*, so as to project therefrom in the path of the springs *a¹*. The springs extend uniformly thin and light their

entire length, and terminate at their free ends, substantially at the point of tangency with said disk, being instantly responsive and quick in their movements, making it possible to run at high speed and without sacrificing precision and certainty of closing-effects. By arranging the springs tangential to the disk and terminating them at substantially their nearest point to the disk, the wheel, *a¹³*, leaves them quickly and their movement is free, certain, quick and sharp. The sluggish action experienced when the springs are engaged back from their ends a considerable distance and carry projecting lugs or engaging devices at their free-ends is entirely obviated, the action is as safe, regular and definite upon reversing the engine as in running ahead, and extreme durability is assured.

It will be understood that the number of wheels *a¹³* is varied according to the conditions of use, the form shown in Fig. 1 being employed for a 4-cylinder engine, each set of contacts cooperating in connection with its own spark coil. In a multi-cycle engine, where one coil only is employed, there is one set of contacts operated by as many wheels as there are cylinders in the engine.

In Figs. 5—7 I have shown 2, 3 and 4 wheels respectively, for use, in a 2-cylinder and in a 3-cylinder and 4-cylinder engine respectively, with one coil, it being understood that where one spark coil only is used for more than one cylinder, I provide the same number of wheels as cylinders.

The back-plate is provided with a handle *a¹⁴* so that it can be rotated slightly, for changing the lead or timing of the apparatus.

The apparatus is inclosed by a suitable cover or cap *a¹⁵* removably secured by any suitable means, as by a bayonet-joint, comprising slots *a¹⁶*, and pins *a¹⁷*, one of which has a thumb-nut *a¹⁸* for fastening the cap in place.

In Fig. 4 I have shown a different arrangement, a hub *a¹⁹* being provided with the desired number of tripping wheels *a¹²* arranged out of step along the hub, instead of in the same radial plane, to cooperate individually with contact springs *a¹* the same as already explained.

In operation, as the rotator or disk is turned the wheel or wheels *a¹³* engage a tangential spring *a¹*, one after the other, and themselves instantly roll or turn in contact therewith in the direction opposite to the movement of their carrier disk, giving a

smooth, perfect contact-motion. By having the wheels a^3 mounted on the rotary carrier disk, the springs a^1 are free and unweighted and can be light and thin, and are instantly responsive to the action of the rotary carrier. They can have no lagging or slowness of movement which would be produced by any projections or contacting devices carried by the springs themselves, but the action is quick and certain, and, although thin and light, there is no danger of injury or undue wear and friction upon reversing the engine. The duration of contact may be regulated by adjusting the member a^2 .

15 I am aware that it is old to employ a spring having a cam lug at its free end to be lifted by a cam notch on the disk or wheel, (see British Patent No. 15,018 of 1901) and I do not claim the same, one object of my invention 20 being to obviate the sluggishness produced by the momentum of said cam lug.

My invention is restricted to having a non-weighted, or uniformly thin, spring engaged by the disk or wheel at its thin, non-weighted 25 extreme tip end, thereby obtaining the quick, sensitive action that enables me to obtain precision of discharges at exceedingly high speeds.

Various modifications may be resorted to 30 without departing from the spirit and scope of my invention.

Having described my invention, what I claim and desire to secure by Letters Patent of the United States, is:

35 1. A rotary interrupter, comprising a rotary device provided with a tripping projection, and a series of straight, leaf contact

springs extending tangentially of the path of said tripping projection, an adjustable contact for each spring extending toward the 40 middle of said spring on the side thereof opposite said rotary device, each spring being held rigidly at its outer end in free suspension in the plane of said tangency and being thin, light, non-weighted and uniform in thickness 45 from its support to its extreme free end, the latter terminating substantially at said point of tangency with the path of said tripping projection, and being engaged at its free tip end by the tripping projection as the latter is 50 revolved by said tripping device.

2. A rotary interrupter, comprising a shaft, a carrier disk fast thereon, said disk having a groove, a small tripping wheel freely pivoted in said groove to project beyond said disk, a movable back-plate next to said disk, a series of contact springs and coöperating stationary contacts fixed on said back-plate and extending freely over said groove but out of contact with the walls thereof, said 60 springs being uniformly thin and non-weighted throughout their length, extending tangentially in the path of said tripping wheel, and terminating to be engaged at their tip ends by said wheel, and a handle for rocking 65 said back-plate and contacts with relation to said disk and tripping wheel.

In witness whereof, I have signed my name to this specification in the presence of two subscribing witnesses.

WILLARD E. DOW.
